UNITED STATES PATENT OFFICE.

JACOB A. HYLE, OF CHICAGO, ILLINOIS, ASSIGNOR OF ONE-HALF TO JOHN F. SWEENEY,
OF CHICAGO, ILLINOIS.

COMBINED RAIL-JOINT AND TIE-PLATE.

1,227,146.

Specification of Letters Patent. Patented May 22, 1917.

Application filed October 26, 1916. Serial No. 127,813.

To all whom it may concern:

Be it known that I, JACOB A. HYLE, a citizen of the United States, residing at Chicago, in the county of Cook and State 5 of Illinois, have invented certain new and useful Improvements in Combined Rail-Joints and Tie-Plates, of which the following is a specification.

This invention relates to new and novel 10 improvements in a combined rail joint and tie-plate in which the two ends of the track rails are secured together at a point between two of the supporting ties.

The main object of my invention is to 15 provide a safe, simple, economical, durable and thoroughly efficient rail joint and tie-plate, so constructed as to effectually prevent the pounding or jarring of the rolling stock in passing over the rail ends, since 20 this device will at all times serve to retain the ends of the rails in a level and even position, and at the same time possesses maximum strength.

A further object of the invention is to 25 combine with the rail joint a double tie-plate adapted to rest upon two supporting ties, thereby constituting a bridge plate of metal upon which the meeting ends of the track rails are rested and firmly secured to 30 the railway ties, in connection with splice or fish-plates, each of said plates being provided with a central depending portion adapted to embrace the lower or base flange of the track rail and the outer and under 35 side portion of the bridge or tie-plate, and with a portion extending from either side of said central portion adapted to overlap the end of each track rail and rest in contact with the tread and also the base portion 40 of the rail.

Another object of the invention is to provide a three-piece joint of drop forged steel having interchangeable angle-bars or fish-plates so constructed as to overlap the 45 central underside recessed portion of the base or tie-plate whereby the up and down bouncing movement of the joint and rails is avoided, and sliding or creeping of the track rails is prevented, the said base or tie-plate having means serving to retain the rails always to their proper gage and prevent their sidewise shifting out of alignment.

The foregoing and such other objects as 55 may appear from the ensuing description are attained by means hereinafter more fully

described, and by the combination, construction, arrangement and location of the parts such as illustrated in the accompanying drawings and particularly set forth in 60 the claim appended hereto.

Reference now being had to the accompanying drawings which form a part of this specification and in which similar numerals of reference indicate like parts 65 throughout the several views, it will be seen that:

Figure 1, is a side elevation of the combined rail joint and tie or base-plate embodying my invention. 70

Fig. 2, is a plan view of the same.

Fig. 3, is a plan view of the under side of the base or tie-plate.

Fig. 4, is a transverse sectional view taken on the line 4—4, looking in the direction of the arrow, Fig. 1, and 75

Fig. 5, is a transverse sectional view taken on the line 5—5, Fig. 1.

The preferred construction of my invention is embodied in the form illustrated in 80 the drawings, wherein 1, 1, designates the adjacent ends of two ordinary track-rails which are united by the joint at a point substantially at the central longitudinal portion of a base or tie-plate 2, constituting a bridge piece, having a central section 3 provided at each side thereof with opposite elongated notches or recesses 4, 4, and having a plurality of longitudinal depending strengthening ribs 5—5, arranged between 90 the two supporting ties and serving to properly space the ties apart. The plate 2 is also provided with two broad end sections 6, 6, which are wider than the base flanges of the rails, extending over and 95 adapted to be secured to the ties, each of said sections projecting at both of its side margins outside of or beyond the side margins of said base flanges. Each of the sections 6, 6, is provided with a plurality of integral upward projections 7, two at each side terminating at the outer edge thereof, and one near each end, each projection being semi-circular in form, the upper surface being inclined in an upward and outward 105 direction, and within each of said projections 7, is an opening 8 through which the rail securing spikes are driven.

It will be seen that the projections 7 formed on the plate 2, are so located and 110 arranged on the plate that the inner edges of said projections are adapted to contact

with the outer side edges of the base of the track rail, and serve to keep the track rails in true gage and prevent the outward spreading of the rails. By this construction of plate the ties are also held securely in the position in which they are placed, while the ribbed bridge portion is sufficiently strong, in connection with the angle bars or fish plates, to withstand the weight 10 of the rails and train and transmit it to the ties.

The numeral 9 designates the angle-bars or fish-plates which are alike for both sides of the rails and are adapted to fit at their 15 upper margins against the under surface of the rail-treads and at their lower margins against the top surfaces of the base-flanges of the rails, and the said fish-plates are securely clamped to the rail by the several 20 track bolts 10, and securing nuts 11. At their central parts the said fish-plates are provided at their lower margins with outwardly and downwardly inclined projecting portions 12 which embrace the outer 25 edges of the said base-flanges and the outer edges of the recessed central section 3 of the base or tie-plate 2, their outer marginal parts 13 being directed horizontally inward, so as to extend beneath to overlap and engage the adjacent marginal parts of the 30 said base or tie-plate which is made narrower at its central section than the end portions thereof. The notches or recesses 4, 4, formed in the sides of the base or tie-plate 35 are made of substantially the same length as the downwardly projecting portions 12 of the fish-plates, so that the end surfaces 14, 14 of the said portions 12 abut against or contact with the shoulders 15, 15, formed 40 at the ends of the said notches 4, 4, thereby constituting an interlocking connection between the two fish-plates and the base or tie-plate, and preventing the creeping or running action of the rails or any relative end- 45 wise movement thereof.

Each end portion of the fish-plate 9 which overlaps the track rails is cut away or narrowed, so that the lower flanges will rest in contact inside of the outer side margins of the base flanges of the rails in order 50 to expose the projections 7, formed on the base plate 2, thereby permitting the fastening spikes to be driven therethrough in contact with the margins of the rail-flanges, 55 since it will be seen that the inner edge of each of the spike openings 8 terminates in alinement with the inner edges of each of the projections 7.

It will be perceived that the fish-plates 9 are slightly inclined upwardly and inwardly from their base to the top portion thereof, and surrounding each of the portions which are weakened by punching out 60 openings for the fastening bolts, is formed an excess of metal for reinforcing said por-

tions to avoid breakage at said points, said excess of metal thickening and thereby strengthening the plates 9 at the points 16, and extending around each bolt opening to a point at the lower end of each opening 70 thereby serving to strengthen the plates at said points 16, and at the same time present a vertical face to receive a washer 17 which is secured in contact with the vertical face by the securing nut 11.

While the fastening spikes ordinarily employed in fastening the rail joint and base plate to the ties may be utilized, I preferably use a screw-threaded spike 18, having a rounded head portion 19, the under side 80 of said head portion being inclined or beveled upwardly, and adapted to be snugly seated in contact with the upper inclined surface of the projection 7, and the inclined upper surface of the track rail base. 85 The upper terminal of each spike is provided with a square portion 20 adapted to receive a wrench or other suitable tool for the removal or insertion of the spike, as clearly shown in Fig. 5, of the drawings. 90

It will be seen that at each side of the inclined depending portion 12 of the fish-plates, is a lateral extended shouldered portion 21, serving to reinforce said depending portion and to prevent accidental breakage or severance of the portion 12 at the point where it overlaps and interlocks with the outer margin of the rail base and the base or tie-plate, when subjected to the heavy strain caused by the travel of the 100 rolling stock over the rail joints.

It will be obvious that slight changes in the detail of construction herein referred to may be resorted to without departing from the spirit of my invention.

Having thus described my invention, what I claim and desire to secure by Letters Patent is:—

The combination with the track-rails and cross-ties, of a tie-plate having a central reduced section provided with a plurality of solid integral depending strengthening ribs, and two broad end sections each having a plurality of upward projections formed at each side of the plate with inclined upper surfaces and a spike hole formed therethrough, the inner edge of each projection terminating in alinement and contact with each outer edge of the rail base and the outer edge of each projection terminating in alinement with the outer side edge of the tie-plate, and two fish-plates clamping against the opposite sides of the rail, each fish-plate being inclined inward and upward from its base, the central portion of each fish-plate having a downwardly inclined depending portion adapted to embrace the outer edge of the rail base and tie plate and terminating beneath in contact with the lower surface of the central reduced section 130

of the tie-plate, each fish-plate having a laterally extended reinforcing shoulder formed at each side of its lower embracing portion, and an excess of metal constituting a strengthening portion surrounding each of the bolt openings in each of the fish plates and adapted to form a vertical face thereon around each bolt opening.

JACOB A. HYLE.
